(57) **CLAIM**

We claim the ornamental design for an ice bin and cover assembly for a refrigerator, substantially as shown and described.

DESCRIPTION

FIG. 1 is a perspective view of an ice bin and cover assembly for a refrigerator of the present invention;
FIG. 2 is a front elevational view thereof;
FIG. 3 is a right side elevational view thereof;
FIG. 4 is a left side elevational view thereof;
FIG. 5 is a top plan view thereof;
FIG. 6 is a bottom plan view thereof; and,
FIG. 7 is a rear elevational view thereof.

The broken line portions of the drawings are for illustrative purposes only and form no part of the claimed design.
